Primary Examiner — Eric L Goodman*Assistant Examiner* — Benjamin L. Gray(74) *Attorney, Agent, or Firm* — Law Office of Bill Naifeh(57) **CLAIM**

The ornamental design for a door stop as substantially as shown and described.

DESCRIPTION

FIG. 1. is a perspective view of a door stop showing my new design;

FIG. 2. is a front view thereof;

FIG. 3. is a rear view thereof;

FIG. 4. is a right side view thereof;

FIG. 5. is a left side view thereof;

FIG. 6. is a top view thereof; and,

FIG. 7. is a bottom view thereof.

An adjustment bolt is shown in broken lines for illustrative purposes only and forms no part of the claimed design. The dashed lines and stippling represent surface shading on the enclosure material and are not part of the claimed design.
